UNITED STATES PATENT OFFICE.

EZRA B. SMITH, OF CHICAGO, ILLINOIS.

LEVER-BUTTON.

1,074,905.

Specification of Letters Patent.

Patented Oct. 7, 1913.

Application filed February 13, 1913. Serial No. 748,135.

To all whom it may concern:

Be it known that I, EZRA B. SMITH, a citizen of the United States, residing at Chicago, county of Cook, State of Illinois, have invented a certain new and useful Improvement in Lever-Buttons, and declare the following to be a full, clear, and exact description of the same, such as will enable others skilled in the art to which it pertains to make and use the same, reference being had to the accompanying drawings, which form a part of this specification.

My invention relates to fastening together the meeting ends of two members, particularly two members of a piece of wearing apparel such as bands, belts and collars and has for its primary object to produce a simple device which may be used in connection with ordinary buttons and buttonholes to apply considerable power to draw together the two parts to be connected, make the connection secure, and facilitate the undoing of the fastening when it is desired to disconnect or unbutton the members which are fastened together.

My invention is particularly applicable to the buttoning of shirt collars of the type now generally worn by the male sex and, viewed in one of its aspects, the invention may therefore be regarded as comprising a collar button and buttoner which makes it easy to put on a collar the edges of which are intended to lie close together without danger of soiling or breaking the collar, which will cause such a collar to remain securely buttoned, and which will make it easy to unfasten or unbutton the collar.

The various features of novelty whereby my invention is characterized will herein-after be pointed out with particularity in the claims; but, for a full understanding of my invention and of its objects and advantages, reference may be had to the following detailed description taken in connection with the accompanying drawing, wherein:

Figure 1 is a front view of a collar having my invention applied thereto, illustrating the first step in fastening the collar; Fig. 2 and Fig. 3 are views similar to Fig. 1, illustrating the second and the third step, respectively, in the fastening or buttoning operation; Fig. 4 is a front view of the collar completely buttoned; Fig. 5 is a perspective view of the attachment forming the subject of this invention; Fig. 6 is a bottom plan

view of the front portion of the collar completely buttoned as shown in Fig. 4; Fig. 7 is a view similar to Fig. 5, showing a modification; Fig. 8 is a plan view of a still further modification; Fig. 9 is a side view of the device shown in Fig. 8 shown in operative relation to a collar button.

In the drawings I have illustrated my invention as applied to a particular type of collar and, for the sake of simplicity I shall confine the detailed description to the particular arrangement illustrated; but it will of course be understood that my invention is not limited to any particular type of collars or even to collars of any kind as it may be used to advantage in many situations where two members are ordinarily buttoned together as well as in connection with other things which it is desired to fasten together detachably.

Reference being had to the first six figures of the drawing, 1 represents a collar comprising an inner portion having at its ends flaps, 2 and 3, adapted to be overlapped, these flaps extending beyond the ends of the outer turned-down portion, 4. Collars of this type are fastened in front by providing the overlapping flaps with registering button holes through which is passed a button carried by or passing through the shirt band. In many of the styles of collars of this kind it is the intention to have the front edges of the turned-down portions 4 lie very close together and, in any event, these edges must lie near enough together to permit the outermost of the two flaps to be slipped well in under the downturned portion on the opposite side. This makes it difficult to button the two flaps together, the difficulty becoming greater as the gap at the front of the closed collar diminishes, collars being very often soiled or broken in the act of putting them on.

In accordance with my invention I have provided a simple attachment which permits one of the flaps to be buttoned in the usual way upon a collar button while the other is buttoned upon the attachment which is in turn detachably mounted on and movable relative to the usual collar button so as to serve as a lever by which the loose end of the collar is drawn in place, and thereafter locked in place, and which, by a reverse action releases the loose end of the collar freely and thus permits the collar to

be unbuttoned without requiring a button to be pulled out of a buttonhole while the collar is under tension.

The attachment may of course take various forms. In the arrangement shown in Figs. 1 to 6, the attachment comprises a small elongated flat plate, 5, of suitable metal. In this plate is an elongated slot, 6, extending lengthwise thereof and having an enlargement, 7, at one end. The enlarged end of the slot preferably lies at a considerable distance from the corresponding end of the plate, this portion of the plate determining the initial length of the lever arm 10 through which power is applied in the buttoning operation. The opposite end of the plate is folded inwardly upon itself as indicated at 8, enough space being left between the inwardly-projecting ear thus formed and the body of the plate to permit the head of an ordinary collar button whose shank lies in the slot 6 to pass beneath the ear. The slot 6 extends far enough toward the upturned end of the plate to bring a portion 15 of the slot beneath the ear and just above the end of the slot, preferably at the extreme end is a button 9, which will be practically co-axial with a collar button lying in the adjacent end of the slot 6. At the other end 20 of the plate there is a hook or shoulder, 10, projecting outwardly from the same side as the ear 8 on one of the long edges of the plate.

In using the device, the flap 2 of the collar is first buttoned upon the usual collar button 11 as indicated in Fig. 1 and the flap 3 is buttoned upon the button 9 on the attachment. The main collar button is then slipped through the enlarged end, 7, of the slot in the attachment so that the condition 25 of the parts is as shown in Fig. 1. It will be seen that there is no strain on the collar at the time the flap 2 is buttoned in place and neither is there any strain on the collar at the time the flap 3 is buttoned to the attachment. The buttoning of the attachment to the main collar button is accomplished while the front edges of the collar are separated perhaps an inch or more, depending upon the length of the slot, so that 30 the buttoning of the attachment on the main collar button is easily accomplished.

With the parts in the positions indicated in Fig. 1, the end of the attachment at 35 which the hook 10 is placed is grasped and drawn outwardly and at the same time laterally to a slight extent so as to bring the shank of the main collar button into the main portion of the slot. The attachment, 40 fulcrumed on the shank of the main collar button serves as a lever to draw the two ends of the collar together and, as the two ends of the collar approach each other, the leverage increases so that the greatest lever- 45 age is available at the time the collar is

naturally brought under the greatest tension, namely when the button 9 is in proximity to the button 11. It will be seen that the pull on the loose end of the collar is a straight pull toward the main collar button, that is, in the circumferential direction, there being no lifting or pulling down of the loose end of the collar as it is drawn into position. When the attachment reaches the vertical position shown in Fig. 2 the shank of the main collar button has been brought into the extreme end of the slot just 50 behind the collar button 9 and thereafter, unless it should be desired to have the collar button slightly eccentric in the final closed position, no further movement of the loose end of the collar takes place as the attachment is swung upwardly into the position indicated in Fig. 3. In this latter position the hook or shoulder 10 engages with the bottom edge of the end of the band or inner member of the collar to which the flap 3 is attached; as best shown in Fig. 6 and a further upward movement of the attachment is prevented. The free end of the attachment is prevented from dropping down from the position shown in Fig. 3 by the person or clothing of the wearer just at the base of the neck. The flap 3 which still lies on the outside may now be slipped 55 under the opposite side of the collar so that the completely buttoned collar has the appearance illustrated in Fig. 4. When it is desired to take the collar off, the free end of the attachment is grasped and it is swung 60 around in a clockwise direction until the parts assume the positions shown in Fig. 1, the strain on the collar being entirely released and the unbuttoning of the attachment from the main collar button being simple and easy.

Instead of carrying the auxiliary collar button on an up-turned and in-turned ear as shown in Fig. 5, the auxiliary collar button may be carried directly upon the body 65 of the plate as indicated in Fig. 7; the plate 12 in this figure having the slot 6 enlarged as at 7, and having also the shoulder or ear 10. The auxiliary collar button 13 is located in the vicinity of the narrow end of the slot 6 and has a shank or stem long enough to raise the head of the auxiliary collar button above the head of the collar button lying with its shank in the slot, thus preventing the main collar button from interfering 70 with the flap at the loose end. In this arrangement the auxiliary button may easily be placed so that when the collar is buttoned the two collar buttons will be slightly out of alignment with each other.

In Figs. 8 and 9 I have shown a third arrangement which has some features in common with the other two forms. Referring to these figures, 14 represents a small flat plate having a hole, 15, through which 75

the head of an ordinary collar button 16 may be slipped. A lever 17 is pivoted on the plate, as at 18, at one side of the hole. On one end of the lever is an auxiliary collar button, 19, while on the other end is a laterally-projecting hook or shoulder, 20, corresponding to the member 10 in the other two forms. In using this device, the first flap of the collar is buttoned in the usual way; 10 the second flap is buttoned upon the button 19; the plate is then slipped over the main collar button; and the lever is swung around in a counter-clockwise direction through an angle of 180 degrees so as to bring the auxiliary collar button in front of and approximately in alinement with the main collar button. The parts are preferably so proportioned that when the collar is in its closed position the axis of the auxiliary button lies 15 slightly below a horizontal plane containing the pivotal axis of the lever and consequently a pull on the loose end of the collar tends to swing the lever still further in the counter-clockwise direction and, since the shoulder or hook 20 is in engagement with the lower edge of the inner member of the collar and such further swinging movement of the lever is thereby prevented, the parts are positively locked in position.

30 I claim:

1. A device of the character described, comprising a plate having one end bent back upon itself to form an ear spaced apart from the body of the plate, a button carried by said ear and said plate having an elongated keyhole slot extending along the same from a point approximately beneath said button.

2. A device of the character described, 40 comprising a plate having one end folded back to form an ear separated from the body of the plate, a button on said ear, a shoulder projecting from the opposite end of the plate on the same side as the ear, and the 45 plate having therein a keyhole slot extending from a point approximately beneath the button to a point considerably removed from the opposite end of the plate.

3. A device of the character described,

comprising a plate having one end bent back 50 upon itself to form an ear spaced apart from the body of the plate, a fastener carried by said ear and said plate having an elongated keyhole slot extending along the same from a point approximately beneath 55 said fastener and narrower at the end beneath the ear than at the other end.

4. A device of the character described, comprising a plate having one end folded back to form an ear separated from the body 60 of the plate, a fastener on said ear, a shoulder projecting from the opposite end of the plate on the same side as the ear, and the plate having therein a slot extending from a point approximately beneath the 65 fastener to a point considerably removed from the opposite end of the plate.

5. A device of the character described comprising a body member having an elongated slot extending lengthwise thereof, a 70 projecting button on one side of the body member near one end of the slot, and a lateral projection on said side of the body member at some distance removed from the 75 button.

6. A device of the character described comprising a plate having an elongated slot extending lengthwise therein, a projecting button on one side of the plate adjacent to one end of the slot, and a projection on said side of the plate at some distance beyond the other end of the slot.

7. In combination, a headed button, a member having an auxiliary button at one end and a lateral projection on the other 85 end, and means for detachably mounting said member on said button so as to permit said member to be swung in the plane at right angles to the button and bring the latter and the auxiliary button into approximately axial alinement.

In testimony whereof, I sign this specification in the presence of two witnesses.

EZRA B. SMITH.
